CAR SEAL

Filed June 9, 1922

Inventor
MARTIN J. LINS
By Paul & Paul

ATTORNEYS

UNITED STATES PATENT OFFICE.

MARTIN J. LINS, OF ST. PAUL, MINNESOTA.

CAR SEAL.

Application filed June 9, 1922. Serial No. 567,229.

To all whom it may concern:

Be it known that I, MARTIN J. LINS, a citizen of the United States, resident of St. Paul, county of Hennepin, State of Minnesota, have invented certain new and useful Improvements in Car Seals, of which the following is a specification.

The object of my invention is to simplify and improve the car seal shown and described in my pending application for Letters Patent of the United States, filed April 6, 1922, Serial No. 549,981.

A further object is to provide a simple, inexpensive seal and one which can not be successfully tampered with without detection.

The invention consists generally in various constructions and combinations, all as hereinafter described and particularly pointed out in the claims.

In the accompanying drawings forming part of this specification,

Figure 1 is a perspective view of a car seal embodying my invention,

Figure 2 is a sectional view of the housing or jacket of the seal on the section line 2-2 of Figure 7,

Figure 3 is a sectional view on the line 3-3 of Figure 2,

Figure 4 is a sectional view showing the parts of the seal in position for locking,

Figure 5 is a similar view showing the operation of locking the seal,

Figure 6 shows the parts of the seal in their locking position,

Figure 7 is a sectional view of the jacket or casing, the inner shell of the seal being shown in full lines,

Figure 8 is a sectional view on the line 8-8 of Figure 7,

In the drawing, 2 represents a metallic strip or band of thin material adapted to bend or flex for convenient insertion into the staple or lug of a car door. At one end of this band I provide a housing or casing for the locking parts of the seal. This housing may be made in different ways but I have indicated in Figures 2 and 3 how it may be formed by folding one end of the band. A section 3 of the band forms the bottom of the housing and a folded section 4 the top thereof, and said section 4 has laterally extending wings 5 formed thereon which are folded downwardly and inwardly under the section 3 to form the side walls of the housing. The socket into which the

tongue of the car seal is inserted may be made in different ways, but I prefer to fold a section 6 of the band, providing laterally projecting wings 7 thereon which are folded downwardly and inwardly to form the side walls and bottom of the socket, the ends being open, the outer end to receive the locking tongue and the inner end of the socket having a slot 8 therein, preferably downwardly and inwardly inclined. A link 9 is adapted to enter this slot. The walls of the socket near the middle thereof are provided with an inclined notch 10 extending inwardly toward the center of the socket, as shown in Figures 4 to 7.

The rear wall of the notch 10 has a recess or seat 11 that is adapted to receive the link 9, said link normally resting in said recess when the seal is in its unlocked position, the other end of the link lying in the slot 8. A locking tongue 12 is formed on the other end of the band 2, preferably by folding the band upon itself to provide the desired thickness and when this has been done, the upper edge of the tongue is cut away to form the inclined surface 13 and at the rear of this surface is a downwardly and inwardly inclined notch 14, a shoulder 15 being provided in the rear of the notch above the level of the surface 13. The tongue also is preferably provided with a straight forward edge 16 that is adapted to contact with the forward end of the link 9 and press it forwardly in the slot 8 out of the seat 11.

As the link is pushed out of the seal 11 it drops into the notch 14 in the tongue, sliding also in the notch 10 in the housing, and as the tongue advances the part 15 laps over the slot 10 and prevents the withdrawal of the link therein.

I also provide a spring finger 18, preferably pressed out of the wall of the socket and extending across the slot 8 and having its end 19 projecting beyond the end of the tongue and overhanging the link, so that there will be no possibility of the link working back into the slot 8, and allowing the seal to be unlocked. This tongue closing the slot 8 is an important feature of this present invention, certain changes, which are also important, being made in the arrangement of the slots in the housing and the tongue wherein the other end of the link is engaged.

With this form of seal embodying the

guard or safety finger it will be impossible for any one to manipulate the link and work it back into the slot in the housing to allow the tongue to be withdrawn sufficiently so that the slots in the housing and tongue will register and permit the return of the link to its normal position in the seat of the socket.

I prefer also to provide a lug 20 at the entrance of the notches in the socket wall to overhang the seat 11 and aid in holding the link in place on this seat, ready for use when the locking tongue is thrust into the socket.

I claim as my invention:

1. A car seal comprising a band, a housing at one end provided with a socket having notches in its walls and a tongue at the other end of said band to enter said socket, said tongue having a notch therein, a link having one end fitting within a slot in the end walls of said socket and normally resting at its other end within the notch in said socket, said link being forced out of said slot by the engagement of the tongue therewith, said link when forced out of said slot, dropping into the notches in said socket and tongue, and a spring finger overhanging the slot in said socket and yielding outward to permit the exit of said link and thereafter preventing the return of said link to said slot.

2. A car seal comprising a band, a housing provided with a socket, a tongue at the other end of said band to enter said socket, the end wall of said socket having a slot therein and a link having one end fitting within said slot and supported at its other end by said socket, said link being pressed out of said slot by the engagement of said tongue therewith, and a finger overhanging the slot in said socket and yielding to allow the exit of said link and thereafter preventing the return of said link to said slot.

3. A car seal comprising a band, a housing provided with a socket, a tongue at the other end of said band to enter said socket, the end wall of said socket having a slot therein and a link having one end fitting within said slot and supported at its other end by said socket, said link being pressed out of said slot by the engagement of said tongue therewith, and a finger overhanging the slot in said socket and yielding to allow the exit of said link and thereafter preventing

the return of said link to said slot, the end of said spring finger overhanging the end of said tongue and preventing upward movement of said link thereon.

4. A car seal comprising a band, a housing provided with a socket having notches in its walls and a seat at the entrance to said notches, a tongue at the other end of said band to enter said socket, said tongue having a notch in its longitudinal edge, said socket having a slot in its end wall, a link having one end normally seated in said slot and its other end resting in the seat at the entrance to the notches in said socket, the end of said tongue engaging said link to force it out of the slot in said socket, said link dropping into the notch in the longitudinal edge of said tongue as it is pushed out of the slot in said socket, and means preventing the accidental return of said link to the slot in said socket.

5. A car seal comprising a band, a housing provided with a socket having notches in its longitudinal edge and a seat at the entrance to said notches and a lug projecting from said seat, the inner end of said socket having a slot therein and a link having one end resting in said seat and its other end fitting within the slot in said socket, a tongue adapted to enter said socket and having an end to engage the inner end of said link and force it out of the slot in said socket, said link becoming dislodged from the seat in said socket and dropping into the notch in said tongue, and means preventing the return of said link to said slot.

6. A car seal comprising a housing, a band on one end of which the housing is mounted, a locking tongue provided at the other end of said band, said housing having a socket therein with a slot in its end walls, a link fitting within said slot and mounted to slide in said socket, the end of said tongue engaging said link to force it out of said slot and said tongue having a notch in its longitudinal edge to receive said link for locking said tongue in said socket when the movement of said tongue forces said link out of said slot, and means preventing the return of said link to said socket slot.

In witness whereof, I have hereunto set my hand this 6th day of June, 1922.

MARTIN J. LINS.
